US0D1113472S

(12) **United States Design Patent** (10) **Patent No.:** **US D1,113,472 S**
(45) **Date of Patent:** **** Feb. 17, 2026**

(54) **SMOKE AND CARBON MONOXIDE
DETECTOR**

(71) Applicant: **KIDDE FIRE PROTECTION, LLC**,
Bradenton, FL (US)

(72) Inventors: **David Benedetti**, Carmel, IN (US);
Kenneth Mott, Colorado Springs, CO
(US)

(73) Assignee: **KIDDE FIRE PROTECTION, LLC**,
Bradenton, FL (US)

(**) Term: **15 Years**

(21) Appl. No.: **29/975,035**

(22) Filed: **Nov. 26, 2024**

Related U.S. Application Data

(62) Division of application No. 29/920,720, filed on Dec. 12, 2023, which is a division of application No. 29/827,376, filed on Feb. 18, 2022, now Pat. No. Des. 1,015,174.

(51) **LOC (15) Cl. 10-05**

(52) **U.S. Cl.**

USPC **D10/106.3**

(58) **Field of Classification Search**

USPC D10/46, 49, 104.1, 106.1, 106.2, 106.3,
D10/106.5, 108, 118.2, 121

CPC G08B 17/00; G08B 17/113

(57) **CLAIM**

The ornamental design for a smoke and carbon monoxide detector, as shown and described.

DESCRIPTION

FIG. 1 is a perspective view of a smoke and carbon monoxide detector, showing our new design;

FIG. 2 is a top view of the embodiment shown in FIG. 1; FIG. 3 is a bottom view of the embodiment shown in FIG. 1;

FIG. 4 is a side view of the embodiment shown in FIG. 1; FIG. 5 is another side view of the embodiment shown in FIG. 1;

FIG. 6 is a front view of the embodiment shown in FIG. 1; and,

FIG. 7 is a rear view of the embodiment shown in FIG. 1. The broken lines in the figures are included for the purpose of illustrating portions of the smoke and carbon monoxide detector and form no part of the claimed design.

1 Claim, 5 Drawing Sheets
